WASHING MACHINE

Anders R. Lofstrand, Sr., Washington, D. C.

Application December 14, 1936, Serial No. 115,871

9 Claims. (Cl. 15—76)

This invention relates to a washing machine designed primarily for washing, rinsing, sterilizing and drying drinking glasses, but it is to be understood that a machine, in accordance with this invention is to be employed for any purpose for which it may be found applicable.

The invention aims to provide, in a manner as hereinafter set forth, a machine of the class referred to including a latchable vertically movable combined top brush holding, carrying and setting mechanism for resiliently retaining a group of top brushes in overlapping relation with respect to the closed ends of a group of drinking glasses while these latter are being subjected to washing, rinsing and sterilizing operations.

The invention further aims to provide, in a manner as hereinafter set forth, a machine of the class referred to including a vertically movable combined top brush holding, carrying and setting mechanism capable of being latched in its upper or inactive position and in its lower or active position.

The invention further aims to provide, in a manner as hereinafter set forth, a machine of the class referred to including a vertically movable top brush holding, carrying and setting mechanism capable of being latched at different levels in setting position.

The invention further aims to provide, in a manner as hereinafter set forth, a machine of the class referred to including an open top combined rinsing and sterilizing compartment for receiving a group of washed glasses and a shiftable lid for normally closing said open top when the compartment is not in use.

The invention further aims to provide, in a manner as hereinafter set forth, a machine of the class referred to including an open top washing compartment, a normally closed combined rinsing and sterilizing compartment, a trolley structure for successively positioning a basket of glasses over the washing and combined rinsing and sterilizing compartments to be selectively lowered in the latter, and means operated from the trolley structure for automatically opening the top of the combined rinsing and sterilizing compartment when the trolley structure is shifted from over the top of the washing compartment to over the top of the combined rinsing and sterilizing compartment.

The invention further aims to provide, in a manner as hereinafter set forth, a machine of the class referred to including an elevator element for supporting and lowering a basket containing a group of inverted drinking glasses to

be acted upon, and a latchable vertically movable combined top brush holding, carrying and setting mechanism carried and guided by and slidable relative to said element, and with said mechanisms acting to resiliently retain a group of top brushes in overlapping relation with respect to the upper ends of the glasses of the group of glasses when these latter are lowered by the elevator element.

The invention further aims to provide, in a manner as hereinafter set forth, a machine of the class referred to which is comparatively simple in its construction and arrangement, strong, durable, compact, readily assembled, thoroughly efficient in its use, conveniently repaired when occasion requires, and comparatively inexpensive to build.

To the above ends essentially, and to others which may hereinafter appear, the invention consists of the novel construction, combination and arrangement of parts as will be more specifically referred to and are as illustrated in the accompanying drawings wherein is shown an embodiment of the invention, but it is to be understood that changes, variations and modifications may be resorted to which fall within the scope of the invention as claimed.

In the drawings:—

Figure 1 is a fragmentary view in elevation looking towards one end of the machine,

Figure 2 is a fragmentary view in elevation looking towards the front of the machine,

Figure 3 is a section on line 3—3, Figure 1,

Figure 4 is a top plan view of the base of the trolley structure,

Figure 5 is a top plan view of the base of the elevator element,

Figure 6 is a fragmentary view in top plan of the top brush holding frame forming an element of the latchable vertically movable combined top brush holding, carrying and setting mechanism,

Figure 7 is a section on line 7—7, Figure 3,

Figure 8 is a top plan view of the elevating and lowering lever forming an element of the mechanism aforesaid,

Figure 9 is a sectional detail of the cross head of the elevator element,

Figure 10 is a side elevation of a modified form of a pull-up means for the elevator element, and

Figure 11 is a fragmentary detail, in side elevation, of the means shown in Figure 10.

The machine includes a lower structure formed in a manner to provide washing, combined rinsing and sterilizing and heated air re-

ceiving compartments 2, 3 and 4 respectively. Preferably, the compartments 2 and 3 will be constructed and arranged in the same manner as the washing and rinsing compartments of Patent No. 2,052,835, with this exception that the combined rinsing and sterilizing compartment 3 has its top normally closed by a shiftable lid 5 forming no part of structure 1 and which will be hereinafter referred to. The heated air receiving compartment 4 will be constructed and arranged in the same manner as the heated air compartment of the patent aforesaid with this exception that at its top it is formed with a vertically disposed hollow extension 6 open at its bottom and closed at its outer side, front and rear. The inner side 6^a of extension 6 has its upper end arranged below the top of the extension. The side 6^a inclines upwardly from its upper to its lower end and provides a water drain. The top 6^b of extension 6 is formed with a depressed apertured portion 7 disposed at a downwardly inclination towards and merges into the upper end of the inner side 6^a. The portion 7 is for the same purpose as and is substituted for the apertured plate designated sixty-nine of the patent aforesaid. The inner side 6^a of the extension 6 has its lower end bottom arranged above the compartment 3 to form a slot or passageway 6^c for the lid 5 when the latter is shifted in a direction to open the top of compartment 3. The lower structure 1 will be provided therein with a like arrangement of elements such as shown within the compartments designated fourteen, thirty-seven and forty-seven of such patent. The compartment 2 of structure 1 is shown as containing a body of water 8 and lower rotatable brushes 9. These brushes function for the same purpose as and are to be constructed, arranged and operated in the same manner as the lower brushes, designated fifty-four of the aforesaid patent. No claim is made in this application to the brushes 9 and their arrangement.

The top of structure 1 at one end thereof has secured thereto transversely thereof a flat member 10 constituting a stop for a purpose to be referred to and which is arranged in parallel spaced relation to the inner side 6^a of extension 6. Secured upon the top of the rear walls of the compartments 2, 3 and extending outwardly therefrom is a flat member 12 rabbeted lengthwise of its upper face. Secured upon the top of the front walls of the compartments 2, 3 and extending outwardly therefrom is a flat member 13 rabbeted lengthwise of its upper face. The members 12, 13 are oppositely disposed and extend from the inner side 6^a of the extension 6 to the inner side edge of the member 10. The members 12, 13 form front and rear tracks.

The lid 5 is hinged to the lower end of the inner side of a trolley structure 14 and normally closes the open top of the compartment 3. If the basket of glasses is to be transported from over the compartment 2 to over the top of the compartment 3, the trolley structure is shifted to the left moving the lid 5 in a like direction. As the trolley structure 14 is moved to the left the lid 5 will enter the upper portion of the compartment 4 through the passageway 6^c whereby the compartment 3 will be open at its top. When the machine is not in use, the lid 5 may be folded upwardly as indicated in dotted lines (Figure 2) and suitably latched in folded position to the trolley structure 14.

The structure 14 includes a frame-like base 15 (Figure 4) of rectangular contour which is dis-

posed in transverse relation with the top of the structure 1. The base 15 includes a pair of oppositely disposed side members 16, 17 of angle shape cross section and each formed of an inner horizontally disposed leg 18 and an outer vertically disposed leg 19 (Figure 1). Merging into the ends of side members 16, 17 is a pair of oppositely disposed end members 20, 21 of angle shape cross section and each formed of an inner horizontally disposed leg 22 and a vertically disposed outer leg 23 (Figure 2). The legs 18 and 22 merge into each other and substantially at the points of emergence the base is formed with inwardly opening inclined gullets 24, 25, 26, 27 (Figure 4) for a purpose to be referred to. The 15 intermediate portions of the legs 19 and 22 of the members 20, 21 are inset as at 28 (Figure 4). The leg 18 of the member 16 at each of its ends is formed with an opening and which are indicated at 29, 30. The leg 22 of the end member 21 is 20 provided at each end with an opening and such openings are indicated at 31, 32. The purpose of the openings 29 to 32 inclusive will be referred to. The inset portion of the leg 23 of the member 20 has formed integral with its inner face a pair 25 of spaced parallel stub shafts 33, 34. The inset portion of the leg 23 of the member 21 has formed integral with its inner face a pair of spaced parallel inwardly extending stub shafts 35, 36. The shafts 33, 34 endwise align in parallel spaced relation with the stub shafts 35, 36 respectively. The non-inset portions of one leg 23 are indicated at 37, 38 and the non-inset portions of the other leg 23 are indicated at 39, 40 (Figure 4). Anchored to the outer face of the non-inset portions 37, 38, 39 and 40 by the holdfast means 41 are depending brackets 42. Each bracket consists of a horizontally disposed intermediate arm 43, a vertically disposed upper arm 44 merging at its lower end into the inner end of the arm 43 and a depending vertically disposed lower arm 45 merging at its upper end into the outer end of the arm 43 (Figure 1). The arm 43 offsets outwardly from the arm 45 relative to the arm 44. The arm 44 abuts a non-inset portion and is fixed therewith by the holdfast means 41. The arm 43 extends outwardly for the purpose of positioning the arm 45 outwardly adjacent a rabbeted member 12 or 13 (Figure 4). The brackets depend below the rabbeted members 12, 13, and the arms 45 thereof are substantially of equi-lateral triangular contour and with the base or wider end of the latter merging into an arm 43. Fixed to the lower end of each arm 45 is an inwardly extending stub shaft 46 which is arranged below a rabbeted member 12 or 13. The stub shafts 46 are arranged in spaced pairs and the shafts of each pair are disposed in endwise aligned spaced relation. Revolvably mounted and secured on the stub shafts 33, 34, 35 and 36 are the traction 60 rollers 47. Revolvably mounted on each stub shaft 46 is a combined retaining and friction roller 48 disposed directly below a rabbeted member 12 or 13.

The rabbeting of the members 12 and 13 on their upper faces provides each of said members with a low inner part 49, a high outer part 50 and a vertical shoulder 51 separating said parts (Figure 7). In other words, the rabbet forms a member 12 or 13 with an upper face having a high surface and a low surface separated by the shoulder 51. The rollers 47 travel on the low parts 49 of the members 12, 13 and the shoulders 51 arrest the transverse shifting of the trolley structure relative to the top of the structure 1. 75

The rollers 48 are arranged below and travel against the lower face of the high parts 50 of the members 12, 13 and arrest the upward movement of the trolley structure or in other words in connection with the rollers 47, they slidably secure the trolley structure on its tracks which are formed by the low parts 49 of the members 12, 13.

Secured in the openings 29 to 32 inclusive are vertically disposed sockets 52 in which the lower ends of vertically disposed standards 53 are anchored. Secured upon the upper ends of the standards 53 is a rectangular top plate 54 formed lengthwise thereof with a V-shaped slot 55 (Figure 2) opening at the front of the plate. Mounted on the upper portions of the standards 53 in proximity to the lower face of plate 54 are resilient cushioning sleeves 56. The plate 54 extends, as at 57 (Figure 1) rearwardly from the upper ends of those standards 53 arranged at the rear of the structure 14. Positioned against the said rear standards 53 is the front wall of a vertically disposed casing 58 having its sides 58a (Figure 3) extended forwardly with respect to the said rear standards 53 and secured to the outer side faces of the side members 16, 17 of the base 15 and the side edges of the plate 54. The part 57 of plate 54 has fixed thereto the upper ends of a pair of spaced parallel depending vertically disposed guide rods 59 (Figures 1 and 3) which are arranged within the casing 58. The part 57 of plate 54 is formed with a vertically disposed opening 60 (Figure 1) arranged between and in equi-distant spaced relation to the rods 59. The upper and lower ends of casing 58 are open. Mounted on and lengthwise of the top of plate 54 is an open bottom housing 60a arranged over the rear portion of the slot 55 and also over the opening 60 in the part 57 of the plate 54.

The machine includes an elevator element 61 consisting of a vertically movable carrier 62 (Figure 5) in the form of a rectangular frame having its side members indicated at 63, 64 and its end members at 65, 66. At the corners of the carrier it is formed with outwardly directed inclined ears 67, 68, 69 and 70 for passage respectively through the gullets 24, 25, 26 and 27 of the base 15 when the element 61 is raised and lowered. The said ears are formed with openings 71 for the passage of the lower end terminal portions of the hanger rods 72 (Figures 1 and 3) which bear against the lower face of the ears. The rods 72 are arranged in pairs. The rods of each pair of rods 72 are disposed in parallel spaced relation and are secured at their upper terminal portions to and adjacent the ends of a combined coupling and guide bar 73 disposed lengthwise of the trolley structure 14. Each bar 73 (Figure 1) includes an intermediate part 74 merging at its ends into vertically disposed sleeves 75 formed integral with oppositely extending arms 76 merging into semi-annular guides 77 (Figure 2) riding against a pair of standards 53 (Figures 1 and 2) below the sleeves 56. The bars 73, intermediate their ends, are connected together by a cross head 78 (Figure 2) arranged below the slot 55. Each pair of rods 72 extends upwardly through the sleeves 75 of a bar 73 and carries retaining means 79 (Figure 1) bearing against the upper and lower ends of the sleeves whereby the bars 72 are anchored to the bars 73. The socket members 52 are provided with inwardly extending laterally disposed combined guide and retainers 80 (Figures 1 and 75

for and through which pass the rods 72. Attached at its forward end to the cross head 78, as at 81, is an elevating and lowering member 82, which is shown by way of example as a chain. Secured upon the rear portion of the top of plate 54 and arranged in housing 60a is a vertical bracket 83 formed with a pair of upstanding oppositely disposed arms 84, 85 provided with guide pulleys 86, 87 respectively. The pulley 87 overhangs the opening 60. The member 82 extends up through slot 55 into the housing 60a, over pulleys 86, 87 and depends from pulley 87 through opening 60 into the casing 58. The rear end of member 82 is fixed, as at 88 to a counterbalance 89 which is slidably mounted on the rods 59. The upper face of the carrier 62 is formed with an endless rabbet (Fig. 5) to provide an endless horizontally disposed seat 90 and an endless vertically disposed shoulder 91. The carrier 62 is of such size with relation to the base 15 of the trolley structure to pass through the base when the carrier is raised and lowered. The seat 90 is adapted to receive a basket 92 containing the drinking glasses 93 which are to be lowered into the washing compartment or the rinsing and sterilizing compartment. The shoulder 91 prevents the lateral shifting of the basket 92 relative to the carrier.

The machine includes latchable vertically movable combined top brush holding, carrying and setting mechanism which comprises a skeleton carrier 94 (Figure 3) having a rectangular body part consisting of a front member 95, a rear member 96, a pair of side members 97, 98, outwardly directed inclined arms 99, 100, 101 and 102 integral respectively with the corners 103, 104, 105, 106 of said body part and a transverse brace member at the transverse center of said body part. The said corners are of annular form to provide openings 108 (Figure 6). The side members 97, 98 are of like form and each is provided with spaced parallel annular portions 109, 110 which provide openings 111 (Figure 6). The openings 108, 111 have their walls formed with inwardly extending lugs 112 (Figure 6) for a purpose to be referred to. The outer ends of the arms 99 to 101 have integral therewith semi-annular combined guide and retainers 112a (Figures 3 and 6) which ride against the rods 72. The member 107 is provided with a laterally disposed horizontal arm 113 (Figure 3) intermediate its ends and a pair of upstanding spaced parallel apertured lugs 114 at its center. The members 97, 98 centrally of their outer sides are formed with upstanding pairs of spaced apertured lugs 115, 116 respectively which align with the lugs 114.

The said mechanism includes an upstanding automatically latchable vertically movable holding element 117 (Figures 1 and 2) operating through the slot 55 and formed of an intermediate part 118 upon a rearwardly directed curve, a lower part 119 merging at its top into and extended forwardly and rearwardly at right angles to the lower end of the part 118 and an upper part 120 merging at its lower end into the upper end of and offset forwardly relative to part 118. The part 119 is provided with a vertical slot 121, a lateral arm 122 at its front spaced from its top and bottom thereof, and has its rear portion positioned between and loosely connected to the lugs 114 by a pivot 122a fixed to said lugs and extending through slot 120. The part 119 extends forwardly from lugs 114 and has its arm 122 arranged in superposed relation with respect to arm 75

113 of member 107. The part 120 has a reduced portion 123 with the major portion of its inner edge toothed, as at 124. The part 120 is shoulered on its rear edge as at 125 and has its upper end portion reduced to provide a grip 126 to facilitate the shifting of element 117 when desired to unlock it.

The said mechanism includes a manually shiftable automatically latchable elevating and lowering device 127 for the carrier 94 and element 117. As the latter is coupled to the carrier 94 it is raised and lowered therewith. The device 127 includes a lever 128 (Figures 1 and 8) extending upwardly through slot 55 and formed of a yoke-shaped part 129 having the inner end portions 130 of its arms 131 bifurcated as at 132. The lever 128 includes an upstanding forwardly inclined handle part 133 anchored at its lower end to the base of the part 129. The arms 131 of the part 129 are formed with aligned openings 134 in proximity to their outer ends. The inner ends of the arms 131 have aligned openings as at 135. Pivotally connected to the arms 131 are depending links 136, 137 (Figure 2) of like form. Each link is formed with a yoke-shaped upper end 138 which straddles an arm 131 of part 129 and is pivotally connected with the latter by a pivot 139 extending through an opening 134. The lower end of link 136 is arranged between the lugs 115 and pivotally connected with the latter by a pivot 139a. The lower end of link 137 is arranged between the lugs 116 and is pivotally connected with the latter by a pivot 140. The part 129 of lever 128 is normally disposed at a downward inclination from front to rear with respect to plate 54. The latter has depending therefrom in proximity to its rear end a pair of spaced forwardly inclined hangers 141 to the lower ends of which are pivotally connected as at 142 the lower ends 40 of the arms 131.

The said mechanism includes a compression spring 142 (Figure 1) for the carrier 94 and which also acts as a controlling spring for the elements 117, 127. The spring 142 is interposed between arms 113 and 122. A keeper 143 is for maintaining the said mechanism in top brush setting position against the action of the spring 142. The keeper 143 (Figure 9) is in the form of a tapered lug depending from the cross head 78 centrally of the front of the latter and it selectively coacts with the teeth 124. A vertical strap 144 (Figure 1) is secured to the central portion of the front of the housing 60a and has projecting forwardly therefrom, near its upper end, an upwardly inclined keeper 145 which coacts with the shoulder 125 to prevent the lowering of the element 117 and lever 128 when the said mechanism is in inactive position. The strap 144 has projecting forwardly therefrom near its lower end a downwardly inclined keeper 146 which coacts with one of the teeth 124 to prevent the upward movement of the element 117 and lever 128 when the mechanism is in inactive position. When the mechanism is in inactive position, the teeth 124 are arranged above the keeper 143. When the mechanism is to be moved to active position, the element 117 is first swung forwardly on its pivot to provide for the shoulder 125 to clear the keeper 145 after which the lever 128 is swung downwardly on its pivots lowering carrier 94 and element 117 to the desired extent. As element 117 is lowered the teeth 124 thereof ride over keeper 143. When downward pressure is relieved on lever 128, the spring 142 acting on arm 122 will cause the keeper 143 to coact with one of the

teeth 124 to latch the carrier 94 in position for setting the top brushes 147 relative to the glasses 93.

Secured to the front of the cross head 78 is a guide yoke 153 which surrounds and retains the element 17 in proximity to the front of housing 60a and cross head 78.

With reference to Figures 10 and 11 there is shown a windable spring motor 154 which may be employed, in lieu of the counterbalance 89 for raising the elevator element. The support 154a for the motor 154 is secured in a socket 155 formed in the top plate of the trolley structure. In Figure 10 the elevator is indicated at 156 and the elevating and lowering cable therefor at 157. Figure 11 shows the winding means 158 for the spring 159 of the motor 154. The upper end of the cable 157 is connected to an ear 160 on the drum 161 revolved from the spring 159.

What I claim is:—

1. In a washing machine of that type including top and bottom brushes, an open bottom trolley structure including a top plate, an elevator slidably connected to said structure and including a vertically movable carrier for positioning the work to be acted upon by the brushes of the machine and for removing the work after being acted upon, said carrier being arranged normally within, capable of passing downwardly through said bottom and guided by said structure, a normally raised latchable combined vertically movable yieldable top brush holding, carrying and setting mechanism arranged within said elevator above said carrier and guided by said elevator, and a linkage connecting said mechanism to said structure below said top plate.

2. In a washing machine of that type including top and bottom brushes, an open bottom trolley structure including a top plate, an elevator slidably connected to said structure and including a vertically movable carrier for positioning the work to be acted upon by the brushes of the machine and for removing the work after being acted upon, said carrier being arranged normally within, capable of passing downwardly through said bottom and guided by said structure, a normally raised latchable combined vertically movable yieldable top brush holding, carrying and setting mechanism arranged within said elevator above said carrier, guided by said elevator and a linkage for pivotally connecting said mechanism to said structure below said top plate, said mechanism including an upstanding spring urged holding element having a loose connection at its lower end with the remainder of said mechanism, said holding element and elevator having coacting means for latching said mechanism in lower position.

3. In a washing machine of that type including an open top washing compartment and an open top combined rinsing and sterilizing compartment, a trolley for transporting a group of washed glasses from over the open top of the washing compartment to over the open top of the combined rinsing and sterilizing compartment, and a closure for normally closing the open top of the combined rinsing and sterilizing compartment, connected to said trolley and shifted to open position by the latter when the trolley is shifted from over the top of the washing to over the top of the rinsing and sterilizing compartment.

4. In a washing machine, an elevating and lowering structure for lowering work to a position to be acted upon, a vertically movable mechanism for bodily shifting a plurality of cleaners

20

30

40

45

50

55

60

65

75

to a position to act upon a part of the work, said mechanism arranged slidably vertically in said structure, a vertically movable upstanding holding element arranged within said structure and loosely connected at its lower end to the said mechanism, shiftable means pivotally connected to said structure and to said mechanism for shifting the mechanism to selective position for the cleaners, said element and structure having 10 coacting means for latching said mechanism in selected positions, and means interposed between said mechanism and the lower end of said element for urging the coacting means on said element against the coacting means on said structure.

5. In a washing machine, an elevator and lowering structure for lowering work to be acted upon and for elevating the work when acted upon, a vertically movable mechanism within 20 said structure for bodily shifting a plurality of yieldable cleaners adapted to be carried thereby to a position to act upon a part of the work, a vertically movable upstanding holding element arranged in said structure having its lower end 25 loosely connected with said mechanism, the said mechanism being formed with an arm, the lower end of said element being formed with an arm arranged in superposed relation with respect to said other arm, said element and structure having 30 coacting means for latching said mechanism in lowered position, and a spring interposed between said arms to provide for said mechanism being yieldable when in lowered position and for urging the coacting means on said element 35 against the coacting means on said structure.

6. In a washing machine, an elevator, a vertically movable mechanism for bodily shifting a plurality of cleaners to a position to act on the work to be cleaned, a slidably connected vertically movable upstanding holding element for said mechanism, a pin and slot connection between said mechanism and one end of said element, a shiftable lever for elevating and lowering said mechanism and element in unison, said mechanism, element and lever being arranged in said elevator, said lever being pivotally supported at one end from said elevator, means for pivotally connecting the lever with said mechanism intermediate its ends, means on the elevator and co- 45 acting with said element for latching it to maintain said mechanism in a selected position, and means on said mechanism and interposed between said element and mechanism for urging said element against the said coacting means.

7. In a washing machine, an elevator, a vertically movable mechanism for bodily shifting a plurality of cleaners to a position to act upon work to be cleaned, a slidably connected vertically movable upstanding holding element for 5 said mechanism, a pin and slot connection between said mechanism and one end of said element, a shiftable lever for elevating and lowering said mechanism and element and lever being arranged in 10 said elevator, said lever being pivotally supported at one end from said elevator, means for pivotally connecting the lever with said mechanism intermediate its ends, means on the elevator and coacting with said element for latching it to 15 maintain said mechanism in selected position, means on said mechanism and interposed between said element and mechanism for urging said element against the said coacting means, and means on the elevator and coacting with 20 said element for latching it to arrest the upward and downward movement of said mechanism when the latter is in normal or inactive position.

8. In a washing machine of the character described, a trolley structure, an elevator structure 25 carried thereby for the work to be cleaned, a vertically movable combined holding, carrying and positioning mechanism for a plurality of cleaners arranged within said elevator structure, said elevator structure being provided with means 30 coacting with a part of said mechanism for latching the latter in working position, and said trolley structure being provided with means coacting with the said part of said mechanism for 35 latching the mechanism in non-working position.

9. In a washing machine of the character described, a trolley structure, an elevator structure carried thereby for the work to be cleaned, a vertically movable combined holding, carrying 40 and positioning mechanism for a plurality of cleaners arranged within said elevator structure, said elevator structure being provided with means coacting with a part of said mechanism for latching the latter in working position, and said 45 trolley structure being provided with means coacting with the said part of said mechanism for latching the mechanism in non-working position, the said part of said mechanism being upstanding, having a loose pivotal connection at its lower end, spring controlled and slidably connected to the elevator structure.

ANDERS R. LOFSTRAND, SR.
